UNITED STATES PATENT OFFICE.

WILLIAM H. CURTIN, OF BROOKLYN, NEW YORK.

VALVE.

1,001,624.

Specification of Letters Patent. Patented Aug. 29, 1911.

Application filed February 17, 1911. Serial No. 669,223.

To all whom it may concern:

Be it known that I, WILLIAM H. CURTIN, a citizen of the United States of America, and residing at Brooklyn, in the county of 5 Kings and State of New York, have invented certain new and useful Improvements in Valves, of which the following is a specification, such as will enable those skilled in the art to which it appertains to make and 10 use the same.

This invention relates to steam valves, and the object thereof is to provide an improvement in such valves over that shown and described in my Letters Patent of the 15 United States, bearing date of March 14, 1911, and numbered 987,050, and wherein a removable bonnet is shown, the present invention being for the purpose of obviating the necessity for such bonnet thereby greatly 20 reducing the cost of manufacture of the valve.

A further object is to provide the double seat for the valve stem whereby no leakage may occur with the valve in open or closed 25 position if the stuffing-box be removed.

A further object is to provide a detachable valve disk for the valve stem which automatically finds its seat and which is of such diameter as to be adapted to be passed 30 into one of the ports of the valve in the assembling thereof.

A further object is to provide such a disk with a recess, preferably with inclined walls, on the under side thereof to receive material of a relatively soft nature, such as Babbitt metal or the like.

A further object is to provide a central post in the said recess which is of angular formation in order to prevent the rotation 40 of the said filling material in the disk in the operation of seating the same.

A further object is to provide a mushroom head upon the said disk adapted to enter a correspondingly enlarged portion of 45 the valve stem, a recess being provided in said stem of a shape and size approximating that of the said head.

A further object is to provide means for retaining said disk head in position, comprising a pin or the like, and also to provide a block serving as a closure for the open side of the valve stem recess; and still further objects are to provide such valves which are very simple and of low cost in 50 construction, which are well adapted to the purpose for which they are designed, which

are made of few parts and cannot therefore readily get out of order to require repair and, with these and other objects in mind, my invention consists of a valve as herein- 60 after fully described and claimed.

My invention is fully described in the following specification, of which the accompanying drawings form a part, in which the separate parts are designated by the 65 same reference characters in each of the views, and in which:—

Figure 1 is a central section taken through a valve constructed according to my present invention; Fig. 2 is a fragmentary section 70 thereof on the line 2—2 of Fig. 1; and Fig. 3 is a horizontal section taken on the line 3—3 of Fig. 1.

In the drawings forming a part of this application I have shown a preferred form 75 of embodiment of my invention, comprising a casing *a* having ports *a*² and *a*³, the latter of which is larger than the former, and the valve casing is provided with a seat *a*⁴ adjacent the port *a*², said port being adapted 80 to be closed by a disk *b* resting on the seat *a*⁴.

The casing *a* is provided with an internal screw thread *a*⁵ engaging a similar thread *c* on a valve stem *c*² provided with a handle *c*³ whereby it may be rotated, and said valve 85 stem is also provided with two conical surfaces *c*⁴ and *c*⁵ which are adapted to be seated in correspondingly formed recesses *a*⁶ and *a*⁷, thereby preventing the passage of steam through the valve stem passage of 90 the casing *a*, and said casing is also provided with a stuffing-box *a*⁸ of the usual or any desired construction. The conical portion *c*⁵ of the valve stem is continued to form an enlarged head and is provided with a 95 T-shaped recess *c*⁶ open at one side, as shown in Fig. 2, said open side being adapted to be closed by a block *d* of the same external configuration as the head *c*⁵, said block being held in position by means of a 100 transversely arranged split pin *d*², or its equivalent, or the pin may be used alone without the block *d* if desired, the result being practically the same as when said block is employed.

The disk *b* is provided with a recess therein, on the contacting side thereof, said recess being adapted to be filled with material of a relatively soft nature, such as Babbitt metal or the like, as shown at *b*², 110 and centrally of the said recess is an integral post or other element *b*³, preferably of

angular shape, to prevent the rotation of the Babbitt metal within the disk, and said post may also be provided with grooves, or the equivalent, to produce shoulders thereon 5 in order to more surely maintain the Babbitt metal in position.

The disk *b* carries a post *b*⁴ on the upper side thereof and which is surmounted by an enlarged head *b*⁵ approximately filling the 10 recess *c*⁶ of the valve stem, said post being shown of angular formation, but it will be understood that it may be circular if desired or of any other external configuration, the intent being that it will fit loosely in the 15 head *c*⁶ of the stem, whereby a degree of flexibility results, thus insuring a positive contact of the disk *b* with the seat *a*⁴.

The disk *b* is of a slightly less diameter than the diameter of the port *a*³ and is 20 adapted to be passed thereinto in the assembling of the valve, the valve stem being passed upwardly through the port *a*² until the outer end thereof extends beyond the stuffing-box *a*⁸ after which the handle *c*³ is 25 placed in position and the stem may be manipulated thereby thereafter and, after the mushroom head of the disk has been placed in the recess *c*⁶, and the block *d* placed in position if employed, the valve 30 stem may be rotated through an arc of a circle to permit of the insertion of the split pin *d*², and my valve is assembled and ready for use.

It will thus be seen that my valve does not 35 require a detachable bonnet for the assembling of the stem and disk therein, thus greatly reducing the cost of manufacture thereof, the complete valve being just as efficient, and giving less opportunity for 40 leakage, than if a detachable bonnet were employed, and the cutting of the thread *a*⁵, and valve stem seats *a*⁶ and *a*⁷, as well as other machining in the valve interior is 45 easily possible through the ports *a*² and *a*³ and, while I have shown a preferred form 50 of embodiment of my invention, it will be obvious that changes thereover may be made, within the scope of the following claims, without departing from the spirit of my invention or sacrificing its advantages.

Having fully described my invention, what I claim as new, and desire to secure by Letters Patent, is:-

55 1. In a valve, a casing provided with a plurality of ports and having a valve seat formed adjacent one of said ports, a valve stem provided with a screw thread for a portion of its length and being inwardly inclined at the outer end of said thread and 60 provided with an outwardly flared flange at the inner end of said thread, said valve casing having coöperating seats for the in-

clined and flared portions of said stem, said outwardly flared flange being provided with a T-shaped recess therein, and a valve disk provided with a mushroom head engaged in said recess.

2. In a valve, a casing provided with a plurality of ports and having a valve seat 70 formed adjacent one of said ports, a valve stem provided with a screw thread for a portion of its length and being inwardly inclined at the outer end of said thread and provided with an outwardly flared flange 75 at the inner end of said thread, said valve casing having coöperating seats for the inclined and flared portions of said stem, said outwardly flared flange being provided with a T-shaped recess therein, a valve disk provided with a mushroom head engaged in 80 said recess, and means for holding said disk detachably in said flange.

3. In a valve, a casing provided with a plurality of ports and having a valve seat 85 formed adjacent one of said ports, a valve stem provided with a screw thread for a portion of its length and being inwardly inclined at the outer end of said thread and provided with an outwardly flared flange at 90 the inner end of said thread, said valve casing having coöperating seats for the inclined and flared portions of said stem, said outwardly flared flange being provided with a T-shaped recess therein, a valve disk provided with a mushroom head engaged in 95 said recess, and means for holding said disk detachably in said flange, said means comprising a pin passed through said flange and beneath said mushroom head.

4. In a valve, a casing provided with a plurality of ports and having a valve seat formed adjacent one of said ports, a valve stem provided with a screw thread for a portion of its length and being inwardly inclined at the outer end of said thread and provided with an outwardly flared flange at 105 the inner end of said thread, said valve casing having coöperating seats for the inclined and flared portions of said stem, said outwardly flared flange being provided with a T-shaped recess therein, a valve disk provided with a mushroom head engaged in 110 said recess, and means for holding said disk detachably in said flange, said means comprising a detachable block closing the opening in said flange and means for locking said block in position.

In testimony that I claim the foregoing as my invention I have signed my name in 120 presence of the subscribing witnesses this 8th day of February, 1911.

WILLIAM H. CURTIN.
